[57] CLAIM

The ornamental design for a shoe upper, as shown and described.

DESCRIPTION

FIG. 1 is an elevational view of one side of a shoe upper showing my new design;FIG. 2 is an elevational view of the other side of a shoe upper as shown in FIG. 1;FIG. 3 is a front elevational view of a shoe upper as shown in FIG. 1;FIG. 4 is a rear elevational view of a shoe upper as shown in FIG. 1; and,

FIG. 5 is a top plan view thereof.

The broken line showing of a shoe sole in FIGS. 1-4 is for illustrative purposes and forms no part of the claimed design.FIG. 2

FIG. 4

FIG. 5
